UNITED STATES PATENT OFFICE

DIRK J. SPYKER, OF GRANDVILLE, AND THOMAS G. KINDEL, OF GRAND RAPIDS, MICHIGAN, ASSIGNORS TO KINDEL FURNITURE COMPANY, A CORPORATION OF MICHIGAN

DESIGN FOR A BEDPOST OR SIMILAR ARTICLE

Application filed July 25, 1929. Serial No. 32,206. Term of patent 3½ years.

To all whom it may concern:

Be it known that we DIRK J. SPYKER and THOMAS G. KINDEL, both citizens of the United States, residing at Grandville and Grand Rapids, Kent County, Michigan, respectively, have invented a new, original, and ornamental Design for Bedpost or Similar Article, of which the following is a specification, reference being had to the accompanying drawing, forming a part thereof.

The figure is a perspective view of a bed post or similar article, showing our new design.

We claim:

The ornamental design for a bed post or similar article, as shown.

In witness whereof, we hereunto subscribe our names this 9 day of July, 1929.

THOS. G. KINDEL.
DIRK J. SPYKER.
